UNITED STATES PATENT OFFICE.

SIMON ZINN, OF NEW YORK, N. Y.

DESIGN FOR A BOX.

SPECIFICATION forming part of Design No. 18,683, dated October 9, 1888.

Application filed September 13, 1888. Serial No. 285,346. Term of patent 3½ years.

To all whom it may concern:

Be it known that I, SIMON ZINN, a citizen of the United States, residing at New York, in the county and State of New York, have invented and produced a new and original Design for a Box, of which the following is a specification, reference being had to the accompanying photograph.

This invention relates to a box the body of which is formed to represent the head of Benjamin Harrison.

The accompanying drawing shows a perspective view of my box.

In the drawing, the letter A designates the body of the box, which is formed to represent

the head of Benjamin Harrison. B indicates the lid of the box.

What I claim as new, and desire to secure by Letters Patent, is—

The design for a box herein shown and described, the same comprising the body A, formed to represent the head of Benjamin Harrison, and the lid B, as set forth.

In testimony whereof I have hereunto set my hand and seal in the presence of two subscribing witnesses.
